UNITED STATES PATENT OFFICE.

KARL D. SMITH, OF BATTLE CREEK, MICHIGAN, AND BERNARD SAMELSON, OF NEW YORK, N. Y., ASSIGNEES TO UNION STEAM PUMP COMPANY, OF BATTLE CREEK, MICHIGAN.

ROTARY PUMP.

1,328,061.

Specification of Letters Patent. Patented Jan. 13, 1920.

Application filed June 2, 1919. Serial No. 301,363.

To all whom it may concern:

Be it known that we, KARL D. SMITH and BERNARD SAMELSON, citizens of the United States, residing at Battle Creek, county of 5 Calhoun, and State of Michigan, and at New York city, State of New York, respectively, have invented certain new and useful Improvements in Rotary Pumps, of which the following is a specification.

10 This invention relates to improvements in rotary pumps.

The main object of our invention is to provide an improved rotary pump well adapted for the pumping of milk which does 15 not have a churning action on the milk, is of large capacity, and a structure which facilitates ready cleaning.

Further objects, and objects relating to structural details, will definitely appear 20 from the detailed description to follow.

We accomplish the objects of our invention by the devices and means described in the following specification. The invention is clearly defined and pointed out in the 25 claims.

A structure which is a preferred embodiment of our invention is clearly illustrated in the accompanying drawing, forming a part of this specification, in which:

30 Figure I is a detail view of our improved pump mainly in vertical central section, the rotor being shown in full lines for convenience in illustration.

Fig. II is a detail front view with the 35 outer casing member removed.

Fig. III is a detail section on a line corresponding to line 3—3 of Fig. I.

In the drawing, similar reference characters refer to similar parts throughout the 40 several views.

Referring to the drawing, we preferably provide a yoke-like frame 1. The arm 2 of the frame 1 is adapted to receive the supporting hub-like projection 3 of the inner casing 45 member 4. This inner casing member is internally cylindrical and is provided with a tangentially disposed outlet 5, to which the delivery pipe 6 is connected.

The outer casing member 7 is adapted to 50 fit within the inner casing member and has an overlapping rim 8 provided with ears 9 for the bolts 10 by means of which the outer casing member is detachably secured to the inner. The outer casing member has an in- 55 wardly flared axially disposed inlet exten-

sion 11 to which the supply pipe 12 is secured. The supply pipe 12 is mounted for quick detachment, being provided with a collar or flange 20 secured to the inlet extension 11 by means of the flanged coupling 21.

The rotor shaft 13 has pulleys 14, one of which is loose and the other fixed to the shaft. The rear end of this shaft is mounted in a bearing 15 carried by the arm 65 16 of the yoke-like frame. The other end extends through the hub portion 3 of the inner casing member, a bushing 17 being provided therein.

The rotor comprises a pair of flat oppositely disposed blades 18 formed integrally with the hub 19 which projects into the inlet extension 11, the blades being flared or widened at 20 to extend into the hub,—

see Fig. I.

75 The shaft 13 is provided with a packing 22 and packing gland 23 threaded upon the hub-like projection 3 of the casing.

With this form and arrangement of parts, the structure may be quickly assembled and 80 disassembled for use or for cleaning, and, further, the pump may be used for pumping milk without an objectionable churning action thereon.

Having thus described our invention, 85 what we claim as new and desire to secure by Letters Patent, is:

1. In a rotary pump, the combination of 90 a supporting frame, a casing comprising an inner member having a tangentially disposed outlet and a hub-like projection mounted on said frame, and an outer member detachably mounted upon the inner, said outer portion being provided with an axially disposed inwardly flared inlet extension, a rotor shaft 95 having a bearing in the said hub portion of said inner member, and a single pair of oppositely disposed flat rotor blades provided with a hub mounted on said shaft to project into said inlet extension, the blades 100 being widened at their inner ends to the outer end of the hub.

2. In a rotary pump, the combination of 105 a casing comprising an inner member having a peripherally disposed outlet, and an outer member detachably mounted upon the inner, said outer portion being provided with an axially disposed inwardly flared inlet extension, and a rotor having a single pair of oppositely disposed flat rotor blades 110

- provided with a hub projecting into said inlet extension, the blades being widened at their inner ends to extend into said inlet extension.
- 5 3. In a rotary pump, the combination of a casing having a peripherally disposed outlet, and an axially disposed inwardly flared inlet extension, and a rotor having a single pair of oppositely disposed flat rotor blades
- 10 provided with a hub projecting into said inlet extension, the blades being widened at their inner ends to extend into said inlet extension.
4. In a rotary pump, the combination of a casing comprising an inner member having a peripherally disposed outlet, and an outer member detachably mounted upon the inner, said outer portion being provided with an axially disposed inlet, and a rotor having a single pair of oppositely disposed flat rotor blades.

In witness whereof, we have hereunto set our hands.

KARL D. SMITH.
BERNARD SAMELSON.
